WARNING LENS

Robert I. Nagel, Skokie, Ill., assignor to R. E. Dietz
Company, Syracuse, N.Y.

Filed Sept. 15, 1970, Ser. No. 24,998

Term of patent 14 years

Int. Cl. D26—06

U.S. Cl. D48—32

FIG. 1

FIG. 2

FIG. 3

FIG. 5

FIG. 4

FIG. 1 is a plan view of the front surface of a warning lens embodying my new design, the concentric ring faceting of the rear surface being partially shown for convenience of illustration, it being understood that the lens pattern of the rear surface is visible through the front face;

FIG. 2 is an edge elevational view thereof as viewed from the bottom of FIG. 1;

FIG. 3 is a plan view of the rear surface thereof, the concentric ring faceting being partially shown for convenience of illustration, it being understood that the concentric ring configurations continue uniformly around the rear surface as indicated. The front faceting which would appear through the unfaceted rectangular area on the rear lens surface is omitted for convenience of illustration;

FIG. 4 is a sectional view on the line 4—4 of FIG. 3.
FIG. 5 is a sectional view on the line 5—5 of FIG. 3.

I claim:

The ornamental design for a warning lens, substantially as shown and described.
